UNITED STATES PATENT OFFICE.

JACOB D. HEATER, OF DAYTON, OHIO, ASSIGNOR TO THE BARNEY AND SMITH CAR COMPANY, OF DAYTON, OHIO, A CORPORATION OF WEST VIRGINIA.

CHAIR.

1,150,189.

Specification of Letters Patent. Patented Aug. 17, 1915.

Application filed October 3, 1914. Serial No. 864,724.

To all whom it may concern:

Be it known that I, JACOB D. HEATER, a citizen of the United States, residing at Dayton, in the county of Montgomery and State of Ohio, have invented certain new and useful Improvements in Chairs, of which the following is a specification, reference being had therein to the accompanying drawing.

10 This invention relates to chairs and more particularly to connecting devices for connecting the tiltable back of a chair to the body thereof.

The object of the invention is to provide 15 a connecting device which will be very simple and inexpensive in its construction, which will have a high degree of efficiency and which will permit the back of the chair to assume a variety of positions.

20 In the accompanying drawings Figure 1 is a sectional view of a chair showing the movable back and the connecting device in elevation; Fig. 2 is a rear elevation of a portion of a chair showing the connecting device applied thereto; Fig. 3 is a detail perspective view of the connecting device showing the parts separated; and Fig. 4 is a horizontal sectional view taken on the line α α of Fig. 2.

30 In the accompanying drawings I have illustrated one embodiment of my invention and have shown the same applied to a type of chair commonly employed on parlor cars. In a chair of this type the back is 35 formed in two parts, the outer part 1 being rigidly secured to the body 2 of the chair and constituting a frame upon which is supported a movable inner portion or back 3. It will be understood, however, that the use 40 of the invention is not limited to chairs of this kind, but that it is applicable to chairs and devices of various kinds.

In that embodiment of the invention here 45 illustrated the movable back 3 of the chair is supported upon the frame 1 by means of two springs arranged on opposite sides of the movable back and each having its opposite ends connected respectively with the movable back and the frame of the chair. 50 This manner of supporting the movable back permits the back not only to move about a horizontal axis, but also to have a certain amount of bodily movement, thereby enabling the back to assume any one of a 55 variety of positions. Further, by supporting the back by springs in this manner it is

not necessary that the supporting devices should be arranged in exact alinement, as would be necessary if the back were mounted on fixed pivots. Consequently, the mounting of the back on the frame of the chair is facilitated. The springs employed may be of various kinds. In the present instance I have shown each spring as formed of relatively heavy wire coiled about a horizontal axis, 60 as shown at 4, and having at each end straight extensions 5 and 6 which project on opposite sides of the axis of the coil, and, in the present instance, extend in diametrically opposite directions. Means are provided for 65 attaching one extension of each spring to the movable back and for attaching the other extension to the frame. Preferably, these attachments or connections are made by providing the back and the frame with sockets 70 adapted to receive the respective extensions of the springs. As here shown, that socket which is secured to the frame comprises a plate 7 having one edge turned upon itself, as shown at 8, to form a socket of a diameter 75 slightly greater than the diameter of the extension 6 of the spring, thereby enabling the spring to be readily inserted therein. A similar plate 9 is secured to the back 3 and provided with a similar socket 10 to receive 80 the extension 5 of the spring. These plates may be secured to the respective parts of the chair by means of ordinary wood screws or in any suitable manner, and after they have been so secured it is a comparatively 85 simple matter to insert the extensions of the springs in the respective sockets, and thereby mount the back in position.

It is desirable that some means should be provided to retain the back normally in a 90 position flush with the outer portion of the back or frame 1, and also to limit the rearward or tilting movement of the back. To accomplish this I have provided the frame of the movable back of the chair with coöperating stops. As here shown the frame is 95 provided with a lug 11, which projects beyond the edge thereof and is preferably formed on a plate 12, which may be secured to the frame by means of screws or otherwise. The stops on the movable back, of which there are preferably two, are here shown in the form of a slotted plate 13 which is secured to the edge of the back adjacent to the plate 12, and has its slot of a 100 width sufficient to receive the lug 11 and of such a length that when the lug is in en-

gagement with the rear end thereof the movable back will be substantially flush with the fixed frame of the chair. The front end of the slot is so arranged that the lug 11 will engage it and check the movement of the movable back before it has been tilted far enough to cause injury. In the present instance the slotted plate 13 has been formed integral with the socket plate 9 and is thus supported in position by the socket plate. This, however, is an optional construction and the stops may be supported in any desired manner.

The operation of the device will be readily understood from the foregoing description and it will be apparent not only that I have provided a very simple, inexpensive device which can be quickly and easily applied to the chair, but that I have provided a device which allows the back a wide range of movement and permits the same to accommodate itself to various positions of the occupant of the chair.

While I have shown and described one embodiment of my invention, I wish it to be understood that I do not desire to be limited to the details of construction shown and described, for obvious modifications will occur to a person skilled in the art.

Having thus fully described my invention, what I claim as new and desire to secure by Letters Patent, is:—

1. In a chair, a frame having side members, springs secured to the respective side members and a back arranged between said side members and supported by said springs, said springs being secured to said back between its upper and lower ends.

2. In a chair, a frame comprising side members, a movable back arranged between said side members, and springs interposed between the opposite sides of said back and the adjacent side members of said frame, between the upper and lower ends of said back, and forming the sole support for the back.

3. In a chair, a frame comprising side members, a movable back arranged between said side members, coiled springs interposed between the opposite sides of said back and the adjacent side members of said frame to support said back for both bodily and turning movements relatively to said frame, and means to secure one end of each of said springs to said back between the upper and lower ends thereof and to secure the other end of each of said springs to the adjacent side member of said frame.

4. In a chair, a frame comprising side members, a movable back arranged between said side members, springs coiled about horizontal axes and arranged in spaces between the opposite sides of said back and the re-

spective side members of said frame to support said back for both bodily and turning movements relatively to said frame, each of said springs having two extensions, and sockets secured to said back and the respective side members of said frame to receive the respective extensions of said springs.

5. In a chair, a frame comprising side members, a movable back arranged between said side members, plates having vertical sockets secured to the respective sides of said back and to the respective side members of said frame, the plates on said back being positioned above the respective plates on said frame, springs coiled about horizontal axes and each having its ends extending upwardly and downwardly, respectively, and adapted to enter the respective sockets on said back and on the side members of said frame.

6. In a chair, a frame comprising side members, and a back movably mounted between said side members, springs interposed between the opposite sides of said back and the respective side members of said frame, between the upper and lower ends of said back, and forming the sole support for said back, and a stop to limit the movement of said back in either direction.

7. In a chair, a frame comprising side members, and a back movably mounted between said side members, springs interposed between the opposite sides of said back and the respective side members of said frame, between the upper and lower ends of said back, and forming the sole support for said back, a lug secured to one of the side members of said frame, and a slotted plate carried by said back to receive said lug, whereby the ends of said slot form stops co-operating with said lug to limit the movement of said back.

8. In a chair, a frame having side members, a movable back arranged between said side members, a plate secured to said back between its upper and lower ends and having a vertical socket and also having a slotted portion formed integral therewith and extending along the edge of said back, a second plate secured to one of the side members of said frame and having a socket, a coiled spring interposed between said back and said frame and having its end portions adapted to enter the respective sockets, and a plate rigidly secured to said side member of said frame and having a lug arranged to enter the slot in said slotted plate.

In testimony whereof, I affix my signature in presence of two witnesses.

JACOB D. HEATER.
